ZIPPER SHIRT

Morris L. Kaplan, Hazleton, Pa., assignor to The Shirterraft Co., Inc., Hazleton, Pa., a corporation of New York

Application August 16, 1949, Serial No. 110,592

9 Claims. (Cl. 2—128)

1

The present invention relates to slide fastener constructions, particularly useful in connection with garments, notably shirts and similar wearing apparel which it is customary to iron or press.

The primary object of the invention is to provide a construction wherein ironing or pressing of the garment will not cause unsightly embossing or impressing of the slide structure in the overlying cloth layer.

An equally important object of the invention is to provide a built-up construction in which the slide fastener, namely, the stringers in connected relation, is so nested that the overlying cloth layer presents a smooth continuous appearance wholly masking the presence of the slide fastener.

This application is a continuation-in-part of my copending application Serial No. 90,955, filed May 2, 1949, now abandoned.

Referring to the drawings:

Figure 1 is a fragmentary front face view showing the present invention applied where two sections of the garment, e. g., a shirt, are connected by a slide fastener;

Figure 2 is a plan view of a strip having parallel spaced raised portions or ridges and adapted to be carried by one panel or section of the garment and in which the connected stringers shown in Figure 1 are received and nested when the shirt is being ironed;

Figure 3 is an enlarged section on the line 3—3 of Figure 1 with the slide fastener structure nested in the space between the parallel ridges of the strip shown in Figure 2, the relationship being somewhat exaggerated for clearness of illustration;

Figure 4 is a fragmentary front face view similar to Figure 1 and showing a modification of the invention;

Figure 5 is a plan view of a strip similar to Figure 2 showing a modified form of strip having only a single raised portion or ridge;

Figure 6 is a sectional view on the line 6—6 of Figure 4 and similar to Figure 3;

Figure 7 is a front view of a modified construction and illustrating the manner in which the slider members are initially embossed into the shirt facing;

Figure 8 is a section on the line 8—8 of Figure 7; and

Figure 9 is a detail view of a strip of the type shown in Figure 5 provided with a thermoplastic layer for the purpose of producing the initial embossment.

The invention will be described in connection

2

with a man's shirt for purposes of illustration, it being understood that the construction is useful wherever recourse is had to slide fasteners.

Referring to Figure 1, the shirt front is shown with its sections 10—11 connected by a slide fastener of conventional character indicated as a whole at 12 and having the usual interengaging stringers 13—14.

The longitudinal edges of the shirt opening 10 are connected at the front, there being an overlying edge 15 and an underlying edge 16. The underlying edge 16 has the material outfolded as at 17 with the margin of the folded portion stitched at 18. Spaced inwardly from the stitching 18 is a stringer tape 19 carrying the stringers 13 and which is stitched at 20—21 to the section 10 of the shirt, as shown in Figure 3, and is coextensive with the shirt opening.

As shown in Figure 3, the section 11 of the shirt has an outfolded portion 22 to which is stitched at 23 a stringer strip 24 carrying the stringer 14, also coextensive with the shirt opening.

Stitched at 25 to the section 11 at a point spaced inwardly from the folded edge 22 is a combined covering layer and slider structure receiving or nesting member coextensive with the shirt opening and indicated as a whole at 26. This member 26, as shown in Figures 1 and

30 3, is plane and uninterrupted on its outer surface as at 27, and covers and conceals the slide structure when the stringers thereof are interengaged. Further, as best shown in Figure 3, this member 26 on its inner side, has a nest or longitudinally extending recess 28 for receiving the interengaging stringers, this nest being coextensive with the stringers and located so as to receive them when they are interengaged.

Referring to Figure 3, the member 26 comprises 40 a facing layer 29 which encloses a reinforcing or stiffening strip 30 and the recess forming strip 31 shown in Figure 2. This strip has a flexible or stiff base 32 and spaced parallel ridges 33.

These ridges may be made of cords or threads or plastic strips of a suitable thickness stitched to the base as at 34. The recess or space 28 between the ridges is wide and deep enough and so located as to receive the slider structure when the stringers are interengaged, whereby the facing surface 27 will remain plain and smooth when the shirt is ironed. That is, there will be substantially complete absence of an unsightly embossment or impression as heretofore created when the nest or recess 28 was not provided.

It will be noted that the facing layer 29, as shown

in Figure 3, extends about the reinforcement or stiffening strip 30 being stitched thereto at 36. This facing layer is preferably continuous and extends over the nesting strip 31 being stitched thereto at spaced points 37.

When, as shown in Figures 1 and 3, the stringers are engaged at the shirt opening, the slider structure will be disposed opposite the recess 28. When the slider connected edges are ironed the slider structure will be received in the nest 28, whence the outer surface 27 of the member 26 will be pressed flat and free of unsightly impressions and conceal the presence of the slider structure.

Referring to Figures 1 and 3, it will be noted that the stringers 13 and 14 are disposed interiorly of the edges of the shirt opening, i. e., the stringer 13 being covered by the section 10 and the stringer 14 being covered by the member 26.

This invention may take many forms, the principal feature being a nesting portion or recess 28 for freely receiving the interengaged stringers and which is of such construction that the outer face 27 of the member 26 will be free of embossments upon ironing the connected edges of the shirt opening.

Referring to Figure 5, instead of having a pair of spaced parallel ridges 33, as shown in Figure 2, only a single ridge is employed indicated at 50. This ridge or cord is carried by a backing strip 51 to which it is stitched and the backing strip is stitched to a reinforcing layer 52 of fabric, a single line of stitching 53 being employed for uniting the cord and the strips 52—53, or two or more lines of stitching may be utilized.

Referring to Figures 4 and 6, the assembly, as shown in Figure 5, is stitched to the member 26 by a line of stitching 54 and forms a suitable nest for receiving the slider structure whereby the facing surface 27 will remain plain and smooth when the shirt is ironed.

Referring to Figures 7, 8 and 9, there is illustrated a further embodiment of the invention wherein means are provided for additionally insuring that the slider structure will not be embossed or impressed in the facing surface 27 of the member 26. To this end, the cord 55 is stitched directly to the front section 11 of the shirt, as shown in Figure 8 by a line of stitching 56. A strip of material, as shown in Figure 9 consisting of the backing layer 57 to which is stitched a layer of thermoplastic material 58, as at 59, is interposed beneath the interfolded layer 60 on the inner side of the member 26, as shown in Figure 8. The stringer structure 14 is interposed between the layer 60, and the inner portion of the loop of the shirt section 11 which encloses the cord 55, as shown in Figure 8 at 61, and the whole assembly stitched together as by the single line of stitching 56 or several lines of stitching may be employed to unite the cord, the stringer 14, and the layers 57 and 58 to the member 26 in the manner shown.

The purpose of this construction is to permit the embossment of the layers 58 and 60, as shown at 62 in Figures 7 and 8 to additionally provide pockets for the slider and which will also serve to register the members of the slider and hold them against displacement. This feature is important in that it serves to additionally maintain the surface 27 smooth and plane upon ironing and also helps to prevent catching of the free edges of the shirt front in the slider structure when the same is being operated. In this connection, it will be noted that in all forms of

the present invention the slider structure is so located as to make it extremely difficult for the free edges of the shirt sections to be entangled in the slider structure as it is manipulated.

5 The embossment may be formed in any suitable manner, as by assembling the layers 57 and 58 beneath the layer 60 and attaching the stringer 14 by stitching and then subjecting the assembled structure to a suitable heating and 10 pressing operation which will fuse the plastic layer 58 to impregnate the layer 57 with the plastic and impress the recesses 62 in the layer 60 by using the slider as a molding member. Of course, the entire assembly, as shown in Figure 15 8, can be first produced and then pressed to mold the recesses 62 in the layer 60, if desired.

I claim:

1. A shirt having front sections and a front opening, edges defining said opening, a slide fastener structure having stringers carried by said edges, one of said edges having stitched thereto a covering member provided on its underside with ridge means defining a recess receiving the slide structure when the stringers are in connected relation, the outer face of said covering member being plain and smooth and having a continuous portion extending over the ridge means on the inner side of the covering member.
2. A garment having an opening, edges defining said opening, a slide fastener structure having stringers carried by said edges, one of said edges having a covering member provided on its inner side with a strip having spaced ridges defining a recess receiving the slide structure when the stringers are in connected relation.
3. A shirt having front sections and a front opening, edges defining said opening, a slide fastener structure having stringers carried by said edges, one of said edges having stitched thereto a covering member comprising a layer of thermoplastic material enclosed in a fabric layer, said covering member provided on its underside with ridge means defining a recess receiving the slide structure when the stringers are in connected relation, the outer face of said covering member being plain and smooth and having a continuous portion extending over the ridge means on the inner side of the covering member.
4. A shirt having front sections and a front opening, edges defining said opening, a slide fastener structure having stringers carried by said edges, one of said edges having stitched thereto a covering member comprising a layer of thermoplastic material enclosed in a fabric layer, said covering member provided on its underside with ridge means defining a recess receiving the slide structure when the stringers are in connected relation, the outer face of said covering member being plain and smooth.
5. A shirt according to claim 1 wherein the slide fastener structure includes stringers attached to a stringer tape, the tape of one of said stringers being folded upon itself adjacent said recess.
6. A shirt according to claim 4 wherein the slide fastener structure includes stringers attached to a stringer tape, the tape of one of said stringers being folded upon itself adjacent said recess.
7. A shirt according to claim 4 having a plurality of pockets molded in said recess for registering and receiving the individual slider members.
8. A shirt according to claim 4 having a sec-

ond thermoplastic layer on the underside of the covering member and also enclosed by said fabric enclosing layer, and a plurality of pockets formed in said enclosing layer and said last-mentioned thermoplastic layer for registering and receiving the individual slider members.

9. A shirt according to claim 4 wherein the slider fastener structure includes stringers attached to a stringer tape, said tape being attached to the fabric of said enclosing layer.

MORRIS L. KAPLAN.
